(57) **CLAIM**

The ornamental design for a vehicle light as shown and described.

DESCRIPTION

FIG. 1 is a front, left perspective view of a right vehicle light showing a first embodiment of our new design;

FIG. 2 is a front view thereof;

FIG. 3 is a top view thereof;

FIG. 4 is a bottom view thereof;

FIG. 5 is a left side view thereof;

FIG. 6 is a right side view thereof;

FIG. 7 is a front, right perspective view of a left vehicle light showing a second embodiment of our new design, which is a mirror image of the vehicle light of FIGS. 1-6;

FIG. 8 is a front view thereof;

FIG. 9 is a top view thereof;

FIG. 10 is a bottom view thereof;

FIG. 11 is a left side view thereof; and,

FIG. 12 is a right side view thereof.

The oblique line shading represents that the surfaces have a transparent, translucent, or reflective appearance. The broken lines showing the remainder of the vehicle light form no part of the claimed design.
